UNITED STATES PATENT OFFICE.

ROSWELL VAN BUSKIRK, OF NEWARK, NEW JERSEY.

EXPANSIVE ENVELOPE.

Specification forming part of Letters Patent No. **43,875**, dated August 16, 1864.

To all whom it may concern:

Be it known that I, ROSWELL VAN BUSKIRK, of the city of Newark, in the county of Essex and State of New Jersey, have invented a new and Improved Envelope, to be called an "Expansive Envelope;" and I do hereby declare that the following is a full and exact description of the same, reference being had to the accompanying drawings, and to letters of reference marked thereon.

The nature of my invention consists in putting a fold in the ends and bottom edge of an envelope, for the purpose of allowing it to expand or contract, while the sides are continued flat and parallel to each other. One or more folds may be used, according to the thickness required.

The same fold may be employed to improve a portfolio by putting it in the lower edge, thus allowing the sides thereof to expand parallel with each other.

Figure 1 is a view of the whole unexpanded with tag projecting outward. Fig. 2 is a view of the whole half expanded, with tag projecting outward. Fig. 3 is a view of the whole half expanded, with the tag folded across the end and labeled. Fig. 4 is a view of the whole

fully expanded, with the tag folded across the end and labeled.

A represents the front side of an envelope; B, the flap; C C C, the folds, and D a tag attached to one end of the envelope, on which is labeled or indexed the contents of the envelope. It is also intended as a handle to draw the package out from the depository.

The value of this improvement consists, first, in its portability—when unfilled, the envelope can be compressed and packaged up like other envelopes; second, in its adaptation to parallel expansion of the sides as it is filled; third, having a flat surface for the sides, it can conveniently be used as a writing-board, especially by putting an extra stiffening in one or both sides; fourth, in the tag for indexing the contents of an envelope, as seen at D in Figs. 3 and 4, and also for drawing the package from the depository.

I claim—

The folds C C C and the tag D, for the purposes herein specified.

ROSWELL VAN BUSKIRK.
